Mark Isaacs

UNITED STATES PATENT OFFICE.

MARK ISAACS, OF MINNEAPOLIS, MINNESOTA.

ELECTRIC WATER HEATER.

Application filed January 17, 1927, Serial No. 161,655, and in Canada December 18, 1925.

The invention relates to improvements in electric water heaters and particularly to a comparatively small, large capacity, water heater which can be attached to a cold water tap or faucet and an object of the invention is to provide a heater which when so attached will effectively heat the water passing through the heater upon the tap or faucet being turned on, thereby permitting one to have hot water instantaneously from a cold water tap.

A further object of the invention is to construct the heater in a simple and durable manner and so that it can be conveniently carried about and such that it can be readily connected to the tap and to the customary house lighting circuit.

A further object is to construct the heater so that the water passing therethrough is divided into a considerable number of streams which are separately heated by a surrounding heating coil and further to provide means for distributing and limiting the quantity of water entering the heater from the tap.

With the above more important objects in view, the invention consists essentially in the arrangement and construction of parts hereinafter more particularly described, reference being had to the accompanying drawing, in which:

Fig. 1 is a side view of the heater attached to a tap and connected up with the customary house lighting circuit.

Fig. 2 is an enlarged detailed vertical sectional view centrally through the heater.

Fig. 3 is a horizontal sectional view through the heater, the section being taken at 3—3' Figure 2.

Fig. 4 is a view showing diagrammatically the manner in which the several heating coils are connected.

Fig. 5 is a vertical sectional view at 5—5' Figure 2.

In the drawing like characters of reference indicate corresponding parts in the several figures.

A cylindrical metallic casing 1 is provided, this casing having the ends thereof open and exteriorly screw threaded to receive similar upper and lower closure caps 2 and 3 which are somewhat frusto-conical in shape and are provided at their smaller ends with vertically aligned bosses 4 and 5.

The caps are provided with internal shoul-

ders 6 and the cylinder is lined with a suitable insulating material 7. Similar upper and lower circular hand plates 8 and 9 are inserted within the caps, the plates seating against the shoulders 6. The plates are connected by similar suitably disposed and spaced copper tubes 10 having their ends permanently fastened to the plates in any suitable manner and opening therethrough. The tubes are each surrounded by a tubular insulator 11 such as of mica and the inner faces of the plates 8 and 9 are covered with an insulating material 12 through which the ends of the tubes pass. Each tube is surrounded by a heating wire coil 13, the coil encircling the mica insulator and the several coils are connected in the present instance in series in the manner best shown in Figure 4.

The casing 1 is provided at one side with an outstanding internally screw threaded boss 14 which receives a screw threaded insulating ferrule 15 and feed wires 16 and 17 extend from the customary two-contact plug 18 through the ferrule and connect with the terminal wires of the adjacent heating coil. A semi-spherical perforated sprayer or nozzle 19 is inserted through the upper end of the boss 4 and is suitably suspended in place at the base of the boss as by screw threads indicated at 20. An asbestos packing ring 21 is inserted in the boss 4 above the nozzle and a rubber gasket 22 is placed within the packing ring. The discharge end of the customary cold water service tap or faucet 23 is adapted to pass into the rubber gasket making a water tight joint therewith. The lower boss 5 forms a discharge orifice at the bottom of the heater.

When the heater is to be used for heating cold water, it is placed on the tap or faucet in the manner shown and the plug 18 is connected in the usual manner with the customary house lighting circuit which latter causes the several heating coils surrounding the tubes to become heated and to heat the tubes. The water discharging from the faucet strikes the sprayer or nozzle and is distributed over the top plate 8 and finds its way down through the tubes in thin streams and is heated to a high temperature in passage with the result that the passing water discharges through the orifice or boss 5 very hot.

The holes in the nozzle are so gauged that they limit the quantity of water passing

through the tubes so that no more water is admitted to the tubes than can be heated by the capacity of the coils.

What I claim as my invention is:—

- 5 1. An electric water heater comprising an interiorly insulated cylindrical body having the ends thereof exteriorly screw threaded, interiorly insulated circular heads entering and closing the upper and lower ends of the body, exteriorly insulated metallic spaced water tubes permanently connecting the heads and opening therethrough, frusto-conical, upper and lower caps interiorly screw threaded to receive the exterior threads of the upper and lower ends of the body and provided adjoining the threads with internal shoulders engaging the edges of the heads, said upper cap being fitted with a tap receiving inlet opening and said lower cap being provided with a discharge orifice, a semi-spherical, perforated, water distributing and controlling sprayer located at the inner end of the inlet opening, electric heating coils connected in series and surrounding the tubes and lead wires extending through the side of the cylinder and communicating with the coils.
- 10 15 20 25 2. An electric water heater comprising an interiorly insulated cylindrical body having

the ends thereof exteriorly screw threaded, interiorly insulated circular heads entering and closing the upper and lower ends of the body, exteriorly insulated metallic spaced water tubes permanently connecting the heads and opening therethrough, frusto-conical, upper and lower caps interiorly screw threaded to receive the exterior threads of the upper and lower ends of the body and provided adjoining the threads with internal shoulders engaging the edges of the heads, said upper cap being fitted with a tap receiving inlet opening and said lower cap being provided with a discharge orifice, a semi-spherical, perforated, water distributing and controlling sprayer located at the inner end of the inlet opening, electric heating coils connected in series and surrounding the tubes and lead wires extending through the side of the cylinder and communicating with the coils.

Signed at Minneapolis, Hennepin County, Minnesota, U. S. A., this 4th day of January, 1927.

MARK ISAACS.
